RESISTOR AND METHOD OF MAKING
THE SAMEGeorge J. Mucher, Brooklyn, N. Y., assignor to
Clarostat Mfg. Co., Inc., Brooklyn, N. Y., a corporation of New York

Application May 13, 1948, Serial No. 26,763

3 Claims. (Cl. 201—67)

1

This invention relates to electrical resistance devices, and particularly to high-wattage wire-wound resistors.

Resistors embodying wire-wound rigid cores encased in ceramic tubes or coated with inorganic cement are widely used because the absence of organic materials in their construction makes them inherently capable of high-wattage ratings. However, the cost of manufacture of such resistors is relatively large because even in volume production, each core must be individually wound and handled.

A resistor made according to the present invention provides the high-wattage rating of conventional inorganic rigid core resistors, but is susceptible of mass production and correspondingly reduced manufacturing costs. Instead of a limited length ceramic core on which the resistance wire is wound, I apply the winding to an indefinite length of flexible inorganic strand such as a fiberglass cord. Such a resistance element may be wound on conventional automatic winding machines and may have a length of five hundred feet or more; the length is limited only by the available length of the strand. The wound core may be rewound on reels and stored for future use. It is subsequently only necessary to cut the strand to appropriate lengths, affix terminals and place the unit within a suitable enclosure, all as hereinafter described.

It is therefore an object of the invention to provide an inexpensive resistor formed entirely of inorganic material, and capable of high-wattage performance.

It is another object of the invention to provide a resistance element capable of mass production and resultant low manufacturing costs.

It is a still further object of the invention to provide an improved method of manufacturing high-wattage rating resistors.

Other features and advantages will hereinafter appear.

In the accompanying drawings Fig. 1 is a side elevation of a resistor constructed pursuant to the present invention;

Fig. 2 is a somewhat schematic representation of a core strand partially wound with resistance wire;

Fig. 3 is a longitudinal section of a completed resistor, and

Fig. 4 is a somewhat schematic representation of a method of forming the resistor.

Fig. 1 shows a side elevation of a resistor 10 in which an outer tube 11 of glass, ceramic, or other inorganic insulation material contains a

2

resistance element 12 (see Fig. 3) from which extend the terminal wires 14, 14. The resistance element comprises as in Fig. 2 a flexible body 15 of inorganic material, such as a fiberglass cord on which is wound, pursuant to conventional winding practices, a resistance wire 16 having suitable characteristics.

Fig. 2 represents only a fragment of a length 10 of the cord 15 which may, in a continuous operation, be wound with resistance wire and have a total length of five hundred feet or more. The thus-wound core may be reeled and stored for future use.

15 When the thus-prepared resistance is to be fabricated into the final resistor, the necessary lengths are cut and terminal caps 17, with the leads 14 affixed thereto, are applied to the ends of the sections. The caps may be initially 20 cylindrical and are conveniently crimped about the resistance element for securement thereon and for good electrical connection with the winding 16.

25 The resistance element 12 is then placed within the tube 11 and an inorganic, preferably cold-setting, cement filling is applied. This may advantageously be done in a fixture schematically shown in Fig. 4. The tube 11 is placed within a suitable cavity in an extrusion head 20, said head having a passage 21 communicating with 30 which is a conduit 22 connecting with a suitable reservoir of cement. The cement is preferably a rather thick slurry, and suitable means (not shown) are provided to eject it into the passage 35 21 under pressure, whence it flows into the tube 11 and about the resistance element 12, spacing said element within from the inner wall of the tube and securing it therein. The length of the cavity 21 is preferably so related to the length of 40 the connector lead wire 14, that when the tube 11 is placed within the cavity with the wire resting upon the bottom of the cavity, the resistor unit 12 will be centered with respect to the length of the tube 11. A fixture 23 has an abutment 45 24 which will be engaged by the end of the opposite terminal wire 14 to prevent lateral movement of the element 12 during the cement filling operation. The resultant cement filling 25 secures the unit 12 within the tube 11 and maintains the coils of the winding in mutually insulated relationship.

50 The unit 10 may then be removed from the extrusion head and cleaned of excess cement, following which it is permitted to stand at 55 atmospheric temperature until the mass of

cement 25 has hardened. The resistor is then ready for use.

Thus, among others, the several objects of the invention as aforesaid are achieved. Obviously numerous changes in construction and rearrangement of the parts might be resorted to without departing from the spirit of the invention as defined by the claims. Also the steps of the method might be varied without departing from the spirit of the invention.

I claim:

1. A method of making electrical resistances which includes providing a resistance element embracing a wire-wound flexible body, applying wire-carrying terminal caps to the ends thereof, indenting the outer surfaces of the caps to constrict the same into electrical contact with the adjacent windings to furnish a body assembly with the cap-carried wires extending outwardly and axially therefrom, employing a tube of inorganic insulating material having an overall length and internal diameter greater than the said assembly, introducing the latter into said tube to cause the winding of said body to be spaced from the inner tube face and with the caps housed in the tube at points short of the ends thereof, disposing the tube to extend in a non-horizontal position and introducing through the lower tube end a mass of insulating cement to a volume such that the spaces between the assembly and tube ends is completely filled and the cement extends into the cap indentations; the cap-carrying wires extending beyond the ends of the latter.

2. A resistor comprising a flexible core of insulating material, a coil of wire wound around said core and extending to the ends thereof, caps encasing the ends of said core and constricted around the coil convolutions adjacent such ends to intimately engage the same, terminal leads extending outwardly of and secured to said caps, a tube having a length and bore diameter in excess of the length and external diameter of the core and cap assembly, the tube being concentrically disposed and spaced from the core and the latter having its outer cap surfaces lying at points short of the tube ends, a layer of insulating cement completely filling the

space between said tube and core and extending beyond the outer cap surfaces to maintain all parts of the resistor assembly against movements with respect to each other and said terminal means projecting through the cement layer beyond the cap surfaces.

3. A resistor comprising a flexible core of insulating material, a coil of wire wound around said core and extending to the ends thereof, caps 10 encasing the ends of said core and crimped into contact with the coil convolutions adjacent such ends to intimately engage the same and constrict the coils and core body in line with such crimping, terminal leads extending downwardly 15 of and secured to said caps, a tube having length and bore diameter in excess of the length and external diameter of the core and cap assembly, the tube being concentrically disposed and spaced from the core and the latter having its outer cap surfaces lying at points short of the tube ends, a layer of insulating cement completely filling the space between said tube and core and extending into the cap crimping and beyond the outer cap surfaces to maintain all parts of the 20 resistor assembly against movements with respect to each other and said terminal leads projecting through the cement layer beyond the cap surfaces.
